WORK-HOLDING DEVICE HAVING A BALL
AND SOCKET AS A MEANS FOR UNIVERSAL
ADJUSTMENT

Clemon W. Barker, Wichita, Kans.

Application October 2, 1942, Serial No. 460,584

6 Claims. (Cl. 287—12)

My invention relates to a universal work support. The object of my invention is to provide a work support device to which the work may be attached and then turned to any desired position and rigidly held there for the workman.

A further object is to provide a device of the kind mentioned whose adjusting feature is a ball and socket and the socket being contractable as a means of locking the holding element in any adjusted position.

A still further object is to provide a work holder device of the kind mentioned that may be operated quickly and positively either under mechanical action or hydraulic pressure.

A still further object is to provide a work holding device of the kind mentioned that is strong and sturdy, easy and inexpensive to make, and one that is positive and highly efficient in its operation and work, and also a device that is durable and long lived. These and other objects will be more fully described and explained as this description progresses.

Now referring to the accompanying drawings,

Fig. 1 is a front view of the mechanically operated form of the work holder device.

Fig. 2 is a side view of the work holder device as shown in Fig. 1.

Fig. 3 is a plan view of the work holder device as shown in Fig. 1.

Fig. 4 is a detail vertical sectional view through the work holder device, the view being taken along the line IV—IV in Fig. 2 and looking in the direction of the arrows.

Fig. 5 is a detail sectional view through the hoisting device for the clamp, the view being taken along the line V—V in Fig. 1, and looking in the direction of the arrows.

Fig. 6 is a front view of the hydraulically operated form of the work holding device.

Fig. 7 is a side view of the work holder device as seen from the right of Fig. 6.

Fig. 8 is a plan view of the work holder device as shown in Fig. 6.

Fig. 9 is a detail vertical sectional view of the work holder device, the view being taken along the line IX—IX in Fig. 7 and looking in the direction of the arrows.

Similar numerals of reference designate the same parts throughout the several figures of the drawings.

In Figures 1 to 5 inclusive is shown the mechanically operated form of my improved work holder device which comprises a base element 10 that is provided with holes 11 through which bolts or screws may be passed to fasten the work

holder device to the top of a work bench or other suitable support for the device. Centrally positioned on the base element 10 and integrally formed thereon is an upwardly directed annular portion 10a, the inside of which is threaded as at 12.

At 13 is shown a tubular element, the lower end of which is threaded into the annular portion 10a of the base element 10. The upper end of the 10 tubular element is provided with an outwardly extending annular flange portion 13d that is integrally formed on the tubular element 13.

At the lower portion of the tubular element 13 and on a diametric axis therethrough is positioned 15 a cam shaft 14. The outer end of the cam shaft 14 is provided with a lever arm 15 by which the cam shaft 14 may be revolved. The inner end of the cam shaft is journaled in a bearing 16 formed in the tubular element 13 and on the diametrical axis thereof. Integrally formed on the inner end of the cam shaft 14 and positioned within the hollow portion thereof is a cam 17. On the cam 17 is integrally formed a pin 18 that is in axial alignment with the cam shaft 14 and is journaled 20 in a bearing 19 formed in the tubular element 13 and on an axis common to the cam shaft 14 and bearing 16.

Slidably positioned within the tubular element 13 is a shaft 20 the lower end of which rests on 25 the cam 17 and is movable longitudinally by the action of the cam 17.

At 21 is shown the lower portion of a ball socket which normally rests on top of the upper end of the tubular element 13 and is engageable by the 30 upper end of the shaft 20 so that as the shaft 20 raises under the action of the cam 17 the shaft 20 will engage and raise the lower portion 21 of the ball socket for purposes that will later be made obvious.

40 Rigidly mounted in the flange portion 13d is one end of a pin 22; the other end of the pin 22 projects upwardly from the flange 13d and is slidably seated in a hole 23 in the lower portion 21 of the ball socket.

45 At 24 is shown a ball socket cap element, the lower portion of which encloses the lower portion 21 of the ball socket and also the flange portion 13d of the tubular element 13.

At 25 is a ring that is slidable on the tubular 50 element 13 and is adapted to engage the under side of the flange 13d. The ring 25 is rigidly attached to the ball socket cap 24 by means of bolts 26 that pass through the ring 25 and are threaded into the skirt or lower portion of the ball socket cap element 24.

At 27 is shown a ball resting on the lower ball socket portion 21 and being enclosed by and supporting the ball socket cap element 24. The cap 24 is provided with a slot 28 through which extends a pin 29, the inner end of the pin 29 being rigidly mounted on the ball 27 with the axis of the pin 29 passing through the center of the ball 27. The slot 28 is of such length and in such a position that the pin 29 may be rocked to any position from horizontal to vertical. Also the cap 24 may be revolved about the vertical axis of the tubular element 13 which makes it possible to position the pin 29 at any point about the vertical axis and at any selected angle formed by the vertical axis and the axis of the pin 29. On the outer end of the pin 29 is a plate 30 that is provided with holes 31 through which bolts may be passed to fasten objects to the plate 30 that are to be worked on. It will be understood that curved or deformed plates, clamps of various design and the like may be substituted for the plate 30 to hold particular pieces of work to be worked on.

The operation of the device is as follows. The work to be worked on is attached to the plate 30, whereupon the work may be revolved about the axis of the pin 29 and the vertical axis of the tubular element 13 and also placed in any position from horizontal to vertical to obtain the desired position that the work is to be held. This being done the cam shaft is rocked to the position shown in Figures 4 and 5, whereupon the cam 17 raises the shaft 20 which in turn raises the lower portion 21 of the ball seat to rigidly bind the ball 27 in its adjusted position so as to rigidly hold the work in its adjusted position. The work may be easily and quickly adjusted to any other desired position by revolving the cam shaft so as to drop the shaft 20 and thereby release the ball 27 so that the work may be moved to the new desired position whereupon the cam shaft 14 may again be turned so as to raise the shaft 20 and socket element 21 to rigidly bind and hold the ball and associated parts as above described.

The device shown in Figures 6, 7, 8 and 9 is hydraulically operated and the parts 13, 13a, 21, 22, 23, 24, 25, 26, 27, 28, 29, 30 and 31, and the assembly and operation thereof are identical with those shown in Figures 1 to 5 inclusive, except that the tubular element 13, in Figures 6, 7, 8 and 9, is an oil cylinder in which is positioned a plunger 20a that is slidable longitudinally in the cylinder 13a.

Beneath the plunger 20a is a cup 32 that is also slidable in the cylinder 13a and is preferably made of a flexible material such as rubber or leather that will expand against the wall of the cylinder 13a to make a tight joint to prevent the leakage of the oil from the cylinder 13a.

The base element 10b is provided with a centrally positioned and upwardly extending cup like formation 10c in which is threaded the lower end of the cylinder element 13. The base and cup elements 10b and 10c are provided with an outwardly and upwardly directed cylindrically shaped element 33 in which is positioned a cylinder 34 that is provided with a passage 35 that connects between the cylinders 13a and 34. The passage 35 being smaller than the cylinder 34 provides a ledge 36 at the bottom of the cylinder 34.

In the cylinder 34 is a helical spring 37 the lower end of which rests on the ledge 36 and the upper end of which is seated in a flexible cup 75

element 38 that is slidably positioned in the cylinder 34.

Also slidably positioned in the cylinder 34 is a plunger 39, one end of which rests against the cup 38. The other end of the plunger 39 is engageable by a cam 40, on which is integrally formed a handle element 41. The cam 40 is positioned in a slot 42, cut in the outer end of the cylinder wall 33. The cam 42 is pivotally mounted on a pin or screw 43 that passes through the outer end of the walls of the cylinder wall 33 and the cam 40 in such a manner that the handle 41 and cam 40 may be rocked as indicated by the arrow A whereby the cam 40 actuates the plunger 39 as and for the purpose described.

The operation of the modified form of the device shown in Figures 6 to 9 inclusive is as follows. The work to be worked on may be attached to the plate or holding element 30 and then moved to any desired position as previously described, whereupon the lever handle 40 may be rocked downwardly to the position shown in Fig. 9, whereupon the cam 40 engages the plunger 39 and forces it and the cup 38 downwardly into the cylinder 34 against the pressure of the spring 37 whereupon oil in the cylinder 34 is forced from the cylinder 34 through the passage 35 and into the cylinder 13a to be added to the oil already filling the cylinder 13a whereupon the cup 32 and plunger 20a are forced upwardly with the upper end of the plunger 20a engaging and lifting the lower portion 21 of the ball socket to bind and hold the ball and parts associated therewith the same as previously described.

Now by rocking the handle 41 upwardly in the direction of the arrow A the cam 40 is rocked downwardly and away from the plunger 39 whereupon the spring 37 pushes the cup 38 and plunger 39 toward the cam 40 thereby drawing oil from the cylinder 13a into the cylinder 34 which in turn draws the cup 32 and plunger 20a downwardly into the cylinder 13a thereby dropping the lower portion 21 of the ball socket to release the ball 27 for adjustment as previously described.

Such modifications of my invention may be employed as lie within the scope of the appended claims without departing from the spirit and intention of my invention. Now having fully shown and described my invention, what I claim is:

1. In a work holder device; in combination, a work holding element, a support pin for the work holding element, and a ball, said pin being rigidly carried on said ball, a socket for said ball, and means for contracting said socket to rigidly bind and hold said ball in adjusted positions and said socket being in axial alignment with, and being swivelly supported on one end of a standard.

2. In a work support device; a work holder and a ball, said work holder being rigidly supported by said ball, a ball socket, said ball being seated in said ball socket, said ball socket comprising a ball support section and a cap section, a standard, said ball support section being supported on said standard, said cap section being swivelly mounted on said standard, and plunger means in said standard, said plunger being engageable with the said ball support section and cam means for imparting movement to said plunger and ball support section to bind and hold the ball in adjusted positions between the ball support section and the cap sections of the socket.

3. In a work support device; the combination

of a work holder, a pin and a ball, and a ball socket, said ball socket comprising a ball socket cap element having a skirt thereon and a ball support element slidably positioned within the skirt of the cap, said cap having a slot therein, said slot extending approximately a one quarter turn downwardly from the vertical axis at the top of the cap to a point on the side thereof, said work holder being rigidly supported on said pin, and said pin being rigidly supported on said ball and being also revolvable and movable in said slot, and said ball being positioned in said socket, a standard, said cap being swivelly fixed to one end of said standard, a plunger, said plunger being slideable longitudinally in said standard and engageable with said ball support element for the movement thereof to bind and hold said ball in adjusted positions, and means for actuating said plunger.

4. In a work support device as defined in claim 3, a cam carried on a shaft, said cam and cam shaft being a means for actuating said plunger, said cam shaft being revolvably carried by said standard in such a position that the plunger will rest on the cam and be actuated by the cam upon the revolvable movement thereof by the cam shaft.

5. In a work support device as defined in claim 3, said plunger actuating means comprising a cylinder in which said plunger is slidably mounted therein, a second cylinder, said second cylinder being connected with the first said cylinder, and a plunger slidably positioned in the

second said cylinder, said cylinders being filled with hydraulic material, a cam, and handle means thereon for the rockable moving thereof, said cam being pivotally mounted at the end of 5 the second said cylinder and in engaging position with the second said plunger for the engagement and movement thereof to move the first said plunger for the actuating of the ball support element.

- 10 6. In a work support device as defined in claim
3, said plunger actuating means comprising a
cylinder in which said plunger is slidably
mounted therein, a second cylinder, said second
cylinder being connected with the first said cylin-
15 der, and a plunger slidably positioned in the sec-
ond said cylinder, said cylinders being filled with
hydraulic material, a cam, and handle means
thereon for the rockable moving thereof, said
cam being pivotally mounted at the end of the
20 second said cylinder and in engaging position
with the second said plunger for the engagement
and movement thereof to move the first said
plunger for the actuating of the ball support ele-
ment, a spring, said spring being positioned in
25 the second said cylinder and being under com-
pression between the bottom of the cylinder and
the second said plunger so as to cause the second
said plunger to recede and follow the said cam
as it is revolved away from the second said
30 plunger for the purpose of imparting a similar
withdrawing action of the first said plunger to
release the ball in the ball socket for adjustment.

CLEMON W. BARKER.
